UNITED STATES PATENT OFFICE.

WILLIAM THOMAS MCCOY, OF UTICA, NEW YORK.

METHOD OF WINDING STRIPS.

1,159,781.

Specification of Letters Patent.

Patented Nov. 9, 1915.

Application filed January 24, 1914. Serial No. 814,191.

To all whom it may concern:

Be it known that I, WILLIAM T. MCCOY, a citizen of the United States of America, residing at No. 225 Steuben street, Utica, in 5 the county of Oneida and State of New York, have invented certain new and useful Improvements in the Method of Winding Strips, of which the following is a specification, reference being had therein to the accompanying drawing.

My invention relates to an improved method of winding strips, and I declare that the following is a full, clear, concise and exact description thereof, sufficient to enable 15 one skilled in the art to practise and use the same, reference being had to the accompanying drawings, in which like reference characters refer to like parts throughout.

The method is applicable particularly in 20 winding strips of paper, cloth or the like which have been prepared with some suitable compound or material to fit it for catching flies and other insects that light upon it, as is familiar in the well known 25 case of fly paper. In some forms of such product a strip of paper thus prepared is rolled up in a continuous roll or fold in a series of folds and held in a box or container which, when suitably hung up, allows 30 the strip to swing free in the air. In the form which I have in mind there will be a cover for the container and contents so that the article may be suspended either by the cover or the bottom of the box and the other 35 member of the container being supported by the free end of the strip. In the method heretofore employed in winding or folding these strips, the strip has been continuously wound or rolled from one end to the

40 other, or has been plaited from one end to the other. In my method of winding these strips I do not start at one end and plait or roll the strip continuously upon itself, but I start at the middle of the strip and roll 45 both halves at the same time but in reversed coils. In this way the operation of winding requires only a fraction of the time required in the old way.

I submit in the drawings herewith an 50 illustration of one form of mechanism for practising this invention, in which—

Figure 1 is an end view of a part of the mechanism showing the coil of the strip with the top and bottom of the box secured 55 one at each end of the strip. Fig. 2 is a

side view indicating the features of a suitable machine for practising this invention.

This mechanism consists of a table portion 1, suitably supported, which has revolvably mounted thereon a shaft 2, at one 60 end of which is mounted the prongs 3 and 4. Treadle 5 is provided from which a cord passes to the shaft 2, with several turns of the cord on the shaft so that when the treadle is pressed down the shaft is revolved 65 in a given direction by the unwinding of the coils. A cord 6 is mounted on the shaft and supports a weight 7, which cord is wound on the shaft 2 when the treadle-cord is unwound, so that the release of pressure 70 from the treadle will re-wind the treadle-cord on the shaft in readiness for the winding of another strip.

In Fig. 1 the strip is shown by 8 and the parts of the container by 9 and 10. This 75 figure illustrates how my invention is practised. The operator takes the strip and places it between the prongs 3 and 4 with half the length of the strip on each side. The portion of the strip which comes in contact with the prongs need not be covered 80 with the sticky preparation and it is preferable not to do so. The operator by means of the treadle causes the prongs to revolve which winds up the strip in the fashion indicated in Fig. 1, which brings the parts of the container up close to the spindle, each end of the strip being mounted in one part 85 of the container. When the work has gone to the extent of bringing the top and bottom of the container closely together the strip is withdrawn from between the prongs and the container closed with the strip 90 therein.

My invention, therefore, comprises the 95 new and useful method of packing such strips in a suitable container, as herein set forth, and

What I claim as new and desire to secure by Letters Patent, is:

1. The method of packing a flexible strip in a container which consists in securing one end of the strip to the container, coiling the strip about itself from its center toward both ends at the same time until the strip 105 is substantially wound up, separating the winding means from the coiled strip and housing the coil within the container with the free end of the coil in the top of the container, whereby tension applied to said free 110

end will remove said coil from the container and unroll it from both ends toward the middle.

2. The method of packing a flexible strip
5 in a two-part container which consists in securing opposite ends of the strip to the top and body parts of the container respectively, coiling the strip about itself from its center toward both ends at the same time
10 until the strip is substantially wound up, separating the winding means from the coiled

strip and housing the coil by bringing the two parts of the container together, so that separation of the parts of the container will remove said coil from the container and 15 unroll it from both ends toward the middle.

In testimony whereof I hereunto affix my signature in the presence of two witnesses.

WILLIAM THOMAS MCCOY.
